Primary Examiner — David Muller(74) *Attorney, Agent, or Firm* — Larson & Larson, P.A.;
Frank Liebenow; Justin P. Miller(57) **CLAIM**

The ornamental design for a gas connector, as shown and described.

DESCRIPTION

FIG. 1 is a front perspective view of a gas connector showing my new design;

FIG. 2 is a rear perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof;

FIG. 8 is a rear elevation view thereof; and,

FIG. 9 is a cross section taken along lines 9-9 of FIG. 3.

The recesses of FIG. 1 and FIG. 7 shown in dashed lines form no part of the claimed design.
